CLAIM

The ornamental design for a seal with cap, as shown and described.

DESCRIPTION

FIG. 1 is a top, side, and front perspective view of a seal with cap showing our new design;

FIG. 2 is an front elevation view thereof;

FIG. 3 is a rear elevation view thereof;

FIG. 4 is a side elevation view thereof, the opposite side elevation being a mirror image thereof;

FIG. 5 is a side elevational view thereof with the cap portion in open position;

FIG. 6 is a top plan view thereof; and,

FIG. 7 is a bottom plan view thereof.

The broken line showing of a vessel in FIG. 1 is for illustrative purposes only and forms no part of the claimed design.
